UNITED STATES PATENT OFFICE.

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY.

BALL-MARKER.

1,390,926.

Specification of Letters Patent. Patented Sept. 13, 1921.

Application filed June 17, 1921. Serial No. 478,362.

To all whom it may concern:

Be it known that I, WILLIAM F. REACH, a citizen of the United States, and resident of Springfield, in the county of Hampden 5 and State of Massachusetts, have invented certain new and useful Improvements in Ball-Markers, of which the following is a specification.

The invention is designed to mark golf 10 balls and the like with the owner's name or other identifying mark, and one object of the invention is to provide a simple device which may be manipulated readily by hand, and which is of convenient form for 15 being carried by the user for his individual use.

Other objects of the invention will appear from the following description, and the features of the invention are defined in the 20 appended claims.

In the accompanying drawings:—

Figure 1 is a perspective view of the device;

Fig. 2 a cross sectional view; and

Fig. 3 a longitudinal sectional view.

In these drawings, 1 indicates the main body of the device, which may be formed of sheet metal or other material. In the present illustration of the invention, sheet 30 metal is employed, and the main body 1 is composed of side walls 2, a bottom wall 3, and curved end walls 4. The end walls are turned at their end edges into bead form, but between the points α — α the sides of the 35 main body are free from the beaded construction, and to these side edges the guide portion 5 of the device is attached. This guide portion is formed of one piece of sheet metal, and is composed of inclined 40 guiding walls 6 which are arranged in convergent relation to each other, extending from the side walls of the main body inwardly, and at their inner ends these inclined walls are continued vertically, as at 45 7, and are connected by a cross portion 8. The vertical walls are spaced apart a proper distance to receive the marking means, which in the present embodiment of my invention consists of a line of type which 50 may be produced on a linotype machine. The distance between the vertical walls 7 is about equal to the thickness of the line of type, so that the latter will be held in place mainly by the frictional contact with 55 these vertical parallel walls.

By reason of the inclination of the walls 6 inwardly toward the center of the appliance, a guide-way is thereby formed for the ball which is to be marked.

In the use of the appliance the golf ball 60 is placed on a table or other suitable support, and ink having been applied to the line of type or other marking means identifying the owner of the ball, the device is placed upon the ball in inverted position, that is, 65 with its guide channel disposed downwardly and with its inclined walls or guides 6 resting on the ball, and then by moving the device over the ball and in contact therewith, the ball will roll on the table and will also roll along the guide, and the marking means carried thereby, so that the impression from the marking means will be imposed on or in the periphery of the ball. 70

The device is of elongated form and the 75 guide-way 6—6 extends from one end to the other thereof and is straight from end to end, and this guide-way controls the relative movement of the ball and marking device one to the other, so that the marking 80 will be accurately performed, and there will be no tendency for side slipping or variation. By reason of this guiding function, the relative movement of the ball and the marking device will be in one direction, 85 that is, from end to end of the guide-way.

I do not limit myself to any particular form of support for the ball nor to any particular material of which the device is made, nor do I limit myself to the particular method of using the device above described, though this obviously is the most preferable way of putting the invention into practice. 90

The guiding portion of the device involving the inclined walls 6, the vertical walls 7, and cross wall 8, is formed, as above stated, in one piece, and may be united with the main portion of the device by turning the side edges of the inclined walls 6 over 100 the edges of the side walls of the main portion between the points α — α .

While the frictional contact between the line of type and the vertical walls of the device may be relied on to hold the line of type in place, clamping means may be employed, such as a screw passing through the wall of the main portion to bear upon one of the vertical walls 7 of the guide member of the device. 105

What I claim is:

1. A ball marker consisting of a member having a guide-way for the ball, the sides of which guide-way are convergent inwardly toward the center line of the member, said sides having a space between them for receiving marking means projecting slightly above the bottom of the guide-way to contact with the ball, said marking means being held between the inner adjacent portions of said sides.
2. A ball marker comprising a member to be carried in the hand and pressed down upon and moved over the ball resting on a table or other support upon which said ball may roll, said member having a channel or guide-way for the ball on its under side to control the relative movement of the ball and member to one direction, said member having marking means carried in the guide-way to mark the ball as it passes thereover and as the ball turns in its rolling traversing action.
3. A ball marker comprising a main portion with side and end walls, and a guideway member having its guiding walls attached to the side walls of the main member, extending inwardly toward each other and having vertical walls at their inner ends spaced apart to receive between them marking means, substantially as described.
4. A ball marker comprising a main portion with side and end walls, and a guideway member having its guiding walls attached to the side walls of the main member, extending inwardly toward each other and having vertical walls at their inner ends spaced apart to receive between them marking means, said vertical walls being connected at their edges by a cross wall, substantially as described.
5. In a ball marker, a member having a

longitudinal guide-way or channel for the ball, with marking means therein, and end walls at the ends of the guide-way reaching above the bottom thereof, substantially as described.

6. A ball marking device consisting of a member to be carried in the hand and moved over and in contact with a ball resting on a support, said member having a guide-way on its under side to receive the upper part of the ball with marking means in said guide-way to contact with the ball as the device is moved thereover and as the ball turns, substantially as described.

7. The herein described method of marking a ball, consisting of resting it upon a table or other support, imposing thereon a member having a straight guide-way to receive the upper part of the ball, and with marking means within said guide-way for making an impression upon the ball, and then moving said member over the ball to roll the same along the table to bring different parts of its upper surface into contact with the marking means, substantially as described.

8. A ball marking device comprising a member having a guide-way for the ball extending longitudinally thereof and made up of substantially rigid walls, said device being of elongated form in the direction of the guide-way, and of a width substantially equal to that of the guide-way, said guide-way having an elongated recess at its depressed central portion with marking means therein for marking the ball, when the ball and marking device are moved relative to each other, while in contact.

In testimony whereof, I affix my signature.

WILLIAM F. REACH.
